UNITED STATES PATENT OFFICE.

WILLIAM H. MORGAN, OF ALLIANCE, OHIO, ASSIGNOR TO THE MORGAN ENGINEERING COMPANY, OF ALLIANCE, OHIO, A CORPORATION OF OHIO.

SAFETY DEVICE FOR TRAVELING CRANES AND THE LIKE.

Application filed January 17, 1924. Serial No. 686,758.

To all whom it may concern:

Be it known that I, WILLIAM H. MORGAN, a citizen of the United States, and a resident of Alliance, county of Stark, and State of Ohio, have invented a new and useful Improvement in Safety Devices for Traveling Cranes and the like, of which the following is a specification, the principle of the invention being herein explained and the best mode in which I have contemplated applying that principle, so as to distinguish it from other inventions.

My present improvements, relating, as indicated, to safety devices for traveling cranes, have more particular regard to the provision of means for preventing the accidental dropping of the lifting tackle carried by such cranes due to the breaking of the cable by means of which the tackle in question is attached to the winding drum or drums on the crane. Such breaking of the cable is ordinarily due to the imposition of strain thereon by pulling the tackle up against the crane through failure on the part of the operator properly to control the winding in of the cable; but whether due to this or other cause, the break in the cable is most apt to occur where it is looped around the so-called equalizing sheave.

I propose accordingly to provide suitable means whereby even though the cable may be thus accidentally broken, the lifting tackle will nevertheless be prevented from falling and thus not only causing serious damage but endangering the lives of the workmen below.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:

Fig. 1 is an end view, more or less diagrammatic in character, of a typical traveling crane with lifting tackle carried thereby and having incorporated in the latter my present improved safety device; and Fig. 2 is a side elevation of the same.

As indicated, the crane itself is illu-

strated in diagrammatic fashion, the parts shown including the rails 1, or equivalent supports upon which the trolley 2 travels and the winding drum 3 with cable 4 for raising and lowering the lifting tackle 5. The supports 1 may either be the main girders in the case of a simple type crane, with the trolley 2 arranged to travel directly on such girders, or said supports may be parts of the bridge of a crane which is in turn mounted on suitable rails or fixed supports, in the case of a crane of the type in which such bridge is arranged to move lengthwise of the shop room, while the trolley travels upon the bridge transversely of such room. The lifting tackle may similarly take on various forms, the one shown, which is illustrative merely, consisting of a pulley block provided with a hook 6 for picking up a ladle or other object to be lifted. Two pulleys or sheaves 7 are mounted side by side in such block and the cable 4 passes from drum 3 down and around one such sheave, thence upwardly around an equalizer sheave 8, suitably mounted in the trolley 2, down around the other sheave 7, and finally up and back again onto the winding drum.

It will be understood that the particular construction of the winding drum and method of winding up the cable forms no part of the present invention; however, both portions of the cable are intended to be wound up or unwound simultaneously, the only function of sheave 8 being to take care of any slight stretching of the respective cable portions or inequality in the rates of winding or unwinding thereof. In other words, there is only a relatively slight movement of the loop in the cable which passes around said sheave 8.

The safety device of present interest comprises a transverse bar or plate 10 pivotally hung by means of integral arms 11 from the same pin 8^a that forms the axis of sheave 8, one such arm lying on each side of the sheave, as shown in Fig. 2. Said bar or plate 10 is provided near its respective ends with apertures 12 through which the corresponding portions of cable 4 normally freely pass. However, each such portion has firmly secured thereto, at a point approximately midway between the sheave and such plate or bar, a stop 13, of general annular form, that is too large in diameter to pass through

the corresponding opening 12. Where, as is usual, the cable is composed of wire strands, the enlargement 13 will preferably consist of a ring of suitable metal directly cast onto the portions of the cable in question.

Due to the fact that the looped portion of the cable that passes over equalizer sheave 8 is constantly bent more sharply than is 10 the case at any other point in the cable and furthermore due to the fact that such portion carries at all times the full strain due to the weight of the lifting tackle and the load carried thereby, it is at this point, according to my observation, that such cable 15 almost invariably breaks. Upon such break occurring where my improved safety device is incorporated, as just described, the stops 13 will simply drop into engagement with 20 the cross bar 10 and the dropping of the tackle 5 is thus positively prevented.

Other modes of applying the principle of my invention may be employed instead of the one explained, change being made as 25 regards the mechanism herein disclosed, provided the means stated by any of the following claims or the equivalent of such stated means be employed.

I therefore particularly point out and distinctly claim as my invention:—

1. The combination of lifting tackle; means for raising and lowering said tackle including a pair of sheaves therein, a relatively fixed equalizer sheave near the upper 35 end of the path of travel of said tackle, a cable passing around said sheaves, and a winding drum for said cable; and means adapted to limit movement of the respective portions of said cable that pass around said 40 equalizer sheave away from the latter.

2. The combination of lifting tackle; means for raising and lowering said tackle including a pair of sheaves therein, a relatively fixed equalizer sheave near the upper 45 end of the path of travel of said tackle, a cable passing around said sheaves, and a winding drum for said cable; a plate disposed in fixed relation to said equalizer sheave and extending laterally adjacent to the respective portions of said cable that pass 50 around said sheave; and a stop on each such cable-portion adapted to be engaged by said plate, whereby movement of such cable-portions away from said sheave is limited.

3. The combination of lifting tackle; means for raising and lowering said tackle including a pair of sheaves therein, a relatively fixed equalizer sheave near the upper 55 end of the path of travel of said tackle, a

cable passing around said sheaves, and a 60 winding drum for said cable; a plate disposed in fixed relation to said equalizer sheave having apertures freely permitting normal movement therethrough of the respective portions of said cable that pass 65 around said sheave; and a stop on each such cable-portion adapted to be engaged by said plate, whereby movement of such cable-portions away from said sheave is limited.

4. In a crane of the type described, the 70 combination with the traveling member of said crane; of lifting tackle; means for raising and lowering said tackle including a pair of sheaves therein, an equalizer sheave attached to said traveling member, a cable 75 passing around said sheaves, and a winding drum for said cable carried by said traveling member; and means adapted to limit movement of the respective portions of said cable that pass around said equalizer sheave away 80 from the latter.

5. In a crane of the type described, the combination with the traveling member of said crane; of lifting tackle; means for raising and lowering said tackle including a 85 pair of sheaves therein, an equalizer sheave attached to said traveling member, a cable passing around said sheaves, and a winding drum for said cable carried by said traveling member; a plate supported from said member in a fixed relation to said equalizer sheave and extending laterally adjacent to the respective portions of said cable that pass 90 around said sheave; and a stop on each such cable-portion adapted to be engaged by said plate, whereby movement of such cable-portions away from said sheave is limited.

6. In a crane of the type described, the combination with the traveling member of said crane; of lifting tackle; means for raising and lowering said tackle including a pair of sheaves therein, an equalizer sheave attached to said traveling member, a cable 100 passing around said sheaves, and a winding drum for said cable carried by said traveling member; a plate supported from said member in fixed relation to said equalizer sheave having apertures freely permitting normal movement therethrough of the respective portions of said cable that pass 105 around said sheave; and a stop in each such cable-portion adapted to be engaged by said plate, whereby movement of such cable-portions away from said sheave is limited.

Signed by me, this 14th day of January, 110
1924.

WILLIAM H. MORGAN.
